DEFOLIATING WITH OXIDIZED WHITE OIL EMULSIONS

William H. Brugmann, Jr., Milltown, and Howard L. Yowell, Westfield, N.J., and Louis A. Mikeska, Dunedin, Fla., assignors to Esso Research and Engineering Company, a corporation of Delaware

No Drawing. Filed Dec. 21, 1955, Ser. No. 554,395

10 Claims. (Cl. 71—2.7)

This invention relates to improved compositions and methods for defoliating plants. More particularly it relates to improved aqueous emulsions for carrying out these purposes containing as the active ingredient materials selected from the group consisting of oxidized white oils and their esters.

The importance and desirability of defoliating living plants is well known. Of particular widespread economic importance is the defoliation of cotton, especially since the successful development of the mechanical cotton picker. This latter development has promoted much research and development in the field of artificial defoliation. Use of defoliants thus increases the efficiency of mechanical cotton pickers. They permit farmers to harvest crops without waiting for frost to naturally defoliate the plant.

It has now been found that particular multi component aqueous emulsions having as the active ingredients oxidized white oils or their esters are especially effective defoliants. These emulsions comprise in addition to the active ingredients and water, a mineral spray oil and an oil soluble emulsifying agent. All these four components in combination are necessary to secure the desired defoliating effect without deleteriously affecting the remainder of the plant. The concentrations, as explained in further detail below, are extremely important in this connection as e.g. lesser quantities of the active compounds do not produce the desired results.

The active ingredients of this invention are prepared by non-catalytically oxidizing, as by air or oxygen blowing, an aromatic-free, petroleum white oil at a temperature in the range of about 150° to 190° C. for a time interval in the range of about 2 to 12 hours. The oil is thus oxidized to a peroxide number (milliequivalents of active oxygen per liter of oil) of 10 to 100, preferably 25 to 50, and an oxygen content of about 1 to 20 wt. percent, preferably 5 to 15 wt. percent. The definition of peroxide number set forth above is described in "The Chemical Constituents of Petroleum," by A. N. Sachanen (1945 ed.), at page 332, footnote 89. It is to be understood that the term "active ingredients" as used herein connotes the total white oil oxidized to the level indicated rather than only the oxygenated materials. These latter are a complex mixture of alcohols, acids, aldehydes, acetals, etc., and the efficacy of the active ingredient is believed to be due to the interaction of these materials, particularly the interaction on balance of acids and peroxides. The ranges stated are consequently extremely important in order to obtain the desired results. The white oil starting material is consequently of importance also.

The white oils utilized are naphthenic, aromatic-free oils (U.S.P. petrolatum liquidum heavy) prepared by the well-known exhaustive sulfuric acid treatment of a heavy petroleum distillate to remove substantially all aromatics. The properties of the oil utilized have been found to be quite important in this invention. Physical inspections should lie within the following limits:

2

Molecular weight	200-500
Specific gravity, 60/60 °F.	0.75-0.90
Saybolt viscosity @ 100° F.	50-200
Unsulfonated residue	percent
5 Pour point	°F. <0

Petroleum fractions outside the range of this oil do not yield satisfactory results.

Some typical white oils are: Marcol JX, a U.S.P. light white mineral oil; and XCT white oil, the latter having the following properties:

Dist.:	
I.B.P.	466
15 50%	501
F.B.P.	669
Flash point	215
Gravity	0.84
Mol. wt., ca.	200
20 U. sulf. res.	percent
Percent aromatics	98+
Percent naphthenes	0
Percent paraffins	60
	40

The esters of the oxidized white oils can also be utilized. These esters can be prepared by esterifying with an added alcohol such as butyl alcohol in the presence of an acid catalyst, e.g. acid resins, sulfuric or an aromatic sulfonic acid catalyst, in an amount of from .01 to 1 wt. percent and using an aromatic solvent such as benzene, toluene, etc. The "natural" esters can also be used. This term connotes esters prepared by the interaction of alcohols and acids contained in the oxidized white oil. Natural esters may be made "in situ" by addition of catalyst, refluxing or heating the oxidized oil at 100°-150° C. until no further H₂O is collected and removed in a water trap. It is necessary to use H₂O entraining agents (xylene-toluene).

Natural esters are also among the oxidation products formed by passing air or O₂ through a white oil at 160°-180° C. They result from the "in situ" reaction of alcoholic (—OH) oxidation products with acidic (—COOH) oxidation products. For purposes of testing these "natural" esters as defoliants, they were first extracted from the total mixture of oxidized XCT white oil oxidation products. This was done by adding equal parts of petr. ether and ammoniacal isopropanol (50/50 concentrated aqueous NH₃/IPOH) to the oxidized white oil. The petr. ether phase was reashed with NH₃/IPOH solution, then with water until neutral. The ether was evaporated, leaving the neutral oxidation products referred to as natural esters. It should be understood that when the active ingredient refers to the esters that it connotes ester concentrates as detailed below.

The mineral oil carriers which may be utilized are, for example, any of the normally used horticultural spray oils. For practical reasons these oils will usually be mineral oils, but oils of animal or vegetable origin or synthetic oils are also satisfactory. In general, the oils should be of a relatively bland, non-toxic nature since any composition which would kill the plant outright could not promote the development of the abscission layers which is necessary to successful defoliation. In order to avoid objectionable staining of the cotton fibers, oils with only a fairly light color should be used. These oils typically have a boiling point in the range of 250° to 550° F., a viscosity in the range of 30 to 200 SSU/100° F. and the petroleum oils are predominantly at least 50 wt. percent to 75 wt. percent paraffinic or naphthenic. The synthetic oxygenated fraction known as Oxo bottoms can also be utilized, and are intended to be connoted by the term "mineral spray oil." The preparation and the character of these Oxo bottoms are described in detail

in U.S. Patent 2,586,681. Blends of the mineral spray oil can also be utilized.

If desired, the auxiliary mineral spray oil per se can be excluded by controlling the degree to which the white oil is oxidized. Thus, if only a moderate level of oxidation is achieved, the resulting product is not excessively phytotoxic and does not require dilution in a carrier spray oil to make it predominantly a defoliant—as opposed to a desiccant. Emulsifier would be added as before and the quantity relations maintained.

The emulsifying agents that can be utilized are oil soluble emulsifying agents known to the art. These include by way of example, by trade name and chemical description as follows: Igepol CO-630, alkyl aryl polyoxethylene glycol ether; Acto, petroleum sulfonate; Nonisol 210, polyethylene glycol oleate; Tween 21, polyoxalkylene derivative of sorbitan monolaurate; Triton X45, alkylated aryl polyether alcohol; Mulsor 3CW, long chain fatty acid ester containing multiple ether linkages; and a petroleum sulfonate modified with a minor amount of a non-ionic emulsifier. Blends can be utilized.

The compositions of this invention are thus conveniently made up in the forms of emulsion concentrates containing 5 to 50 wt. percent of the active ingredient, 40 to 90 wt. percent of the mineral spray oil, and 1 to 10 wt. percent of the emulsifier. These concentrates can then be diluted in the field with water so that the emulsion concentrate constitutes from 10 to 50 wt. percent of the total aqueous emulsion formulation. The active ingredient is contained as an emulsion concentrate which is emulsified with water. As stated previously, the concentrations as well as the components themselves are important to secure the desired activity.

The aqueous emulsion is applied to the plants at a rate of 5 to 40 gallons per acre, preferably 5 to 20 gallons per acre. The lower figures are employed in airplane spraying and the upper ones for ground spray equipment. The time of application varies with the plant, e.g., it is most effectively applied to cotton plants when the latter have matured as when 40% of the cotton bolls have opened. Ten days to two weeks is all that is normally required to secure the maximum defoliation. No adverse effect is noted on the crops where the composition of this invention is applied to cotton. It can also be applied to edible dry beans, soybeans, and flax.

The following examples illustrate this invention and indicate test results obtained with the compositions of this invention emulsified with water as well as the preparation of the active ingredients.

EXAMPLE 1

Preparation of oxidized Marcol JX

Marcol JX was oxidized as taught until it contained about 5.1 wt. percent O₂. The details are as follows: 2500 cc. Marcol JX was charged to a 4 liter 3-necked flask fitted with a stirrer, thermometer, condenser and water recovery trap. Oxygen was passed through the white oil at a rate of 40 cc. per minute while stirring and bringing the temperature of the pot up to 170°-180° C. The temperature in the reaction flask was held at this level until 250 cc. of water had been collected in the water removal trap.

EXAMPLE 2

Preparation of n-butyl ester of oxidized XCT white oil

Esterification apparatus (fitted with thermometer, condenser, stirrer and water removal trap) was charged with 2075 g. of oxidized XCT white oil (having 135-200° C. b. pt., acid No. 85 mgms. KOH/gm.). To this was added 400 cc. n-butyl alcohol, 1 gm. toluene sulfonic acid catalyst and toluene as H₂O entrainer. This mixture was stirred and refluxed until 76 cc. of H₂O was removed. The resulting product was water washed, dried

over Na₂SO₄, and stripped under vacuum to remove toluene. After stripping, the remaining product was fractionated at 1 mm. pressure. The fraction boiling at 115-152° C. was tested as a defoliant. Inspections of 115-152 fractions are as follows:

Combining wt.	6260.
Acid No.	9.0.
Sap No.	180.0.
Br ₂ No.	16.
10 .1 double bond/1000 comb. wt.	
V./100° F.	80 SSU.
V./210° F.	36 SSU.
Pour pt.	-60° F.
Flash pt.	345° F.
15 Percent O ₂	12%, est. by difference from C+H.

EXAMPLE 3

Preparation of natural esters of oxidized XCT white oil

Oxidized XCT white oil (b. pt. 135°-225° C.) was taken up in equal quantity of petroleum ether. To this was added equal portion of ammoniacal isopropanol (50% concentrated aqueous NH₃/50% IPOH). The IPOH layer was drawn off in a separatory funnel, thus removing acidic oxidation products as NH₃ salts. The petroleum ether layer was re-extracted with NH₃/IPOH, then washed with H₂O till neutral. Petroleum ether was stripped, the residue representing "natural" esters of oxidized XCT white oil. Inspections:

Combining wt.	5080.
Acid No.	11.2.
Sap No.	131.6.
Br ₂ No.	15.4.
35 .1 double bond/1000 mol. wt.	
V./100° F.	241.5 SSU.
V./210° F.	44 SSU.
Pour pt.	-35° F.
Flash pt.	360° F.

The following data show the relationship of natural ester boiling range to combining wt. and acid No. of XCT white oil natural esters. 15,000 to 300 combining wt. is preferred.

Balling Range	Comb. Wt.	Acid No.
120-145° C.	13,840	4.0
145-165° C.	854	6.5
165-200° C.	528	11.0

EXAMPLE 4

A detailed study of a typical oxidation of a typical white oil follows.

2500 cc. of XCT white oil blown with air (ca. 40 cc./min.) at 150-165° C. H₂O recovered and oil sample analyzed as each 50 cc. of water is collected:

60	ccs. H ₂ O Recovered	Peroxide No.	Organic Peroxide Comb. Wt.	Acid No.	Organic Acid Comb. Wt.
F I	20	71.4	3,333	6.54	11,059
F II	70	47.6	5,000	14.56	3,836
F III	120	40.5	5,882	24.08	2,291
F IV	170	40.0	5,677	34.16	1,622
F V	220	38.0	5,472	36.28	1,576
F VI	270	21.4	11,900	49.84	1,141
F VII	Btms. in pot.			50.40	1,123

EXAMPLE 5

The various active ingredients were applied in the form of aqueous emulsions to cotton plants at the Delta Branch Experiment Station, Stoneville, Mississippi. Each formulation was applied to four hills, each hill containing from 1 to 3 plants. WS-1449 is a 50/50 blend of Bayol D, a

petroleum white oil with Mentor 28, a conventionally refined paraffin oil having an unsulfonatable residue of 85-90%. The blend viscosity is 45 SSU/100° F. The application rate was as indicated. The results were tabulated 10 days to 2 weeks after application. The results were as follows:

Formulation			Applied As—	Applied Rate (Gal./A)	Estimated Percent Defoliation
Active Ingredient, Wt. Percent	Carrier, Wt. Percent	Emulsifier, Wt. Percent			
Oxidized Marcol JX, 10%-----	WS-1449, 85%-----	Mulsor 3CW, 3% Acto 630, 2%-----	25% emuls.	20	65
Oxidized Marcol JX, 20%-----	WS-1449, 75%-----	Mulsor 3CW, 3% Acto 630, 2%-----	25% emuls.	20	65
n-butyl ester of oxidized XCT, W.O., 10%-----	WS-1449, 85%-----	Mulsor 3CW, 3% Acto 630, 2%-----	25% emuls.	20	70-75
Natural esters of oxidized XCT, W.O., 10%-----	WS-1449, 85%-----	Mulsor 3CW, 3% Acto 630, 2%-----	25% emuls.	20	70-75
None-----	WS-1449, 87%-----	Mulsor 3CW, 3% Acto 630, 2%-----	25% emuls.	40	20

The defoliation figure represents the leaf drop/total original leaves times 100. 65 to 70% defoliation is the minimum required for an effective defoliant. The figures presented above demonstrate that about 65% and usually greater defoliation was obtained with compositions of this invention as contrasted to 20% for the control. Greater activity can, of course, be obtained by utilizing higher concentrations of the active materials within the stipulated ranges.

The utilization of the compositions of this invention represents extremely large labor savings and lower growing costs.

It is to be understood that this invention is not limited to the specific examples which have been offered merely as illustrations, and that modifications may be made without departing from the spirit of this invention.

What is claimed is:

1. A method of defoliating a plant which comprises applying to said plant an aqueous emulsion comprising an organic composite of from 5 to 50 wt. percent of an active ingredient selected from the group consisting of oxidized white oils having a peroxide number in the range of 10 to 100 and an oxygen content in the range of 1 to 20 wt. percent and their esters, the starting white oils being naphthenic, aromatic-free oils having the following physical properties:

Molecular weight ----- 200-500
Specific gravity, 60/60° F. ----- 0.75-0.90
Saybolt viscosity @ 100° F. ----- 50-200
Unsulfonated residue ----- percent 95-100
Pour point ----- ° F. <0

from 40 to 90 wt. percent of a relatively non-toxic horticultural mineral spray oil, from 1 to 10 wt. percent of an oil soluble emulsifying agent, said organic composite constituting from 10 to 50 wt. percent of the total aqueous emulsion said emulsion being applied at a rate of 5 to 40 gallons per acre.

2. The method of claim 1 in which the plant being treated is cotton.

3. The method of claim 1 in which the active ingredient is an oxidized light white mineral oil.

4. The method of claim 1 in which the active ingredients are the butyl esters of an oxidized white oil.

5. The method of claim 1 in which the active ingredients are the esters of an oxidized white oil formed by the

in situ reaction of the alcohols and the acids contained in the oxidized white oil.

6. A defoliant aqueous emulsion concentrate composition comprising from 2 to 50 wt. percent of an active ingredient selected from the group consisting of oxidized white oils having a peroxide number in the range of 10

to 100 and an oxygen content in the range of 1 to 20 wt. percent and their esters, the starting white oils being naphthenic, aromatic-free oils having the following physical properties:

25 Molecular weight ----- 200-500
Specific gravity, 60/60° F. ----- 0.75-0.90
Saybolt viscosity @ 100° F. ----- 50-200
Unsulfonated residue ----- percent 95-100
Pour point ----- ° F. <0

from 40 to 90 wt. percent of a relatively non-toxic horticultural mineral spray oil, and from 1 to 10 wt. percent of an oil soluble emulsifying agent.

35 7. The composition of claim 6 in which the active ingredient is an oxidized light white mineral oil.

8. The composition of claim 6 in which the active ingredients are the butyl esters of an oxidized white oil.

9. The composition of claim 6 in which the active ingredients are the esters of an oxidized white oil formed 40 by the in situ reaction of the alcohols and the acids contained in the oxidized white oil.

10. A defoliant aqueous emulsion concentrate comprising 40 to 90 wt. percent of a relatively non-toxic horticultural mineral spray oil, 1 to 10 wt. percent of an oil soluble emulsifying agent, and 5 to 50 wt. percent of an active defoliating agent prepared by the non-catalytic oxygen blowing of a naphthenic, aromatic-free, petroleum white oil, having the following physical properties:

45 50 Molecular weight ----- 200-500
Specific gravity, 60/60° F. ----- 0.75-0.90
Saybolt viscosity @ 100° F. ----- 50-200
Unsulfonated residue ----- percent 95-100
Pour point ----- ° F. <0

55 55 at a temperature in the range of about 150° to 190° C. for a time interval in the range of 2 to 12 hours, such that the resulting oxidized white oil active defoliating agent has a peroxide number in the range of 10 to 100 and an oxygen content in the range of 1 to 20 wt. percent.
